UNITED STATES PATENT OFFICE.

FREDERICK W. BACORN, OF MARYSVILLE, MONTANA.

ELECTRIC SIGNAL FOR MINE-SHAFTS.

SPECIFICATION forming part of Letters Patent No. 479,046, dated July 19, 1892.

Application filed February 27, 1892. Serial No. 422,995. (No model.)

To all whom it may concern:

Be it known that I, FREDERICK W. BACORN, a citizen of the United States, residing at Marysville, in the county of Lewis and Clarke 5 and State of Montana, have invented certain new and useful Improvements in Electric Signals for Mine-Shafts, which are fully set forth in the following specification, reference being had to the accompanying drawing, 10 forming a part hereof, and in which the figure shows a section of a mine-shaft with an elevator-cage in it provided with my improved electric signaling device.

The object of my invention is to provide 15 an electric signaling device for cages of mine-shafts, elevators and other like vehicles to which it may be applicable, whereby signals may at any and all times be made from the cage to the engineer or other parties outside of 20 such vehicle. As at present constructed, there is a rope from the bell in the engineer's room which runs down to the bottom of the shaft, generally outside of the cage, which must be caught by the hands and pulled to 25 ring said bell, a device which is very unreliable and its operation is always more or less difficult when the cage is in slight motion, depending both on its direction and speed, and is impracticable when the cage is running at 30 its usual or required speed. To overcome said difficulties, I have contrived an electrical apparatus, which is constructed substantially as follows, namely:

The cage *a* is held by the usual guides or 35 ways *b*, and raised by a rope *h*, passing over a sheave to a drum wound and unwound by an engine *i*, all of which said parts may be of any known construction. Into the shaft of the mine is passed a wire *d*, insulated from 40 the shaft-timbers and open at its lower end, as shown, and in which the upper end is connected to an electric bell *e* or other signaling device, which is connected through a wire *d'* to earth. On the cage or, as here shown, under its floor is carried a battery *c*, of which one pole is connected to a trolley *f*, which connects that side of the battery with said wire *d*. To the opposite pole of the battery is connected a wire *h*, which runs up through

the cage, and its upper end is connected to the 50 wire hoisting-rope *h*, which, through the operating mechanism *i*, connects to earth, thus completing the electric circuit of the battery, as shown. In said wire *h* and in a suitable place in the cage is placed a push-button *g* 55 to make and break said circuit.

When for any reason the electric circuit cannot be made through the hoisting-rope of the cage *a* or for other reasons may be desired, a second open wire *d'*, like the wire *d*, 60 may be put into the shaft and connected to earth at its upper end, as shown. Said wire is then put into the circuit through the wire *h* above the push-button *g*, which is connected to a trolley *f'*. Said wire *d'* and trolley *f'* 65 and a short piece of the connecting-wire *h* are shown in broken lines, so as to distinguish them clearly from the other parts before mentioned.

It is not necessary that the battery *c* be 70 placed on the cage or vehicle, because it may readily be placed at any convenient point in the circuit, as in the wires *d* or *d'* or in the wire *d'*, as at *x*, it only being necessary in such case to observe that the battery must be 75 placed above the uppermost point reached by the cage at its upper position. When, therefore, the circuit is closed, the return-current will be established through the earth and the signaling device will be operated while the 80 cage is in motion.

What I claim is—

The combination, with a mine-shaft and an electric wire therein extending through its length, electrically open at its lower end and 85 connected at its upper end with signaling mechanism, and a cage provided with a trolley on said wire, of a second open wire extending through the length of the shaft, and a trolley thereon, and a push-button electrically connecting said trolleys and wires, said 90 wires completing the circuit through said signaling mechanism, substantially as specified.

FREDERICK W. BACORN.
